UNITED STATES PATENT OFFICE.

ROBERT A. STUBBS, OF DALLAS, TEXAS, ASSIGNOR OF THREE-FOURTHS TO G. W. GRISWOLD, OF DALLAS, TEXAS.

MECHANISM FOR COMPRESSING AND SHEETING LOOSE MATERIALS.

1,248,747.

Specification of Letters Patent.

Patented Dec. 4, 1917.

Application filed May 1, 1915. Serial No. 25,176.

To all whom it may concern:

Be it known that I, ROBERT A. STUBBS, a citizen of the United States, residing at Dallas, in the county of Dallas and State of Texas, have invented certain new and useful Improvements in Mechanisms for Compressing and Sheeting Loose Materials, of which the following is a specification.

My invention has relation to a mechanism for compressing and sheeting loose materials such as feed, grain, fiber or other materials and in such connection it relates more particularly to the construction and arrangement of the parts of the mechanism whereby the material after being compressed may be still further flattened and sheeted prior to its delivery from the mechanism.

In a companion application for patent filed of even date herewith and Serial Number 25,174, I have described and claimed broadly a series of coöperating mechanisms and means constituting a shredding machine, by means of which machine, loose fibrous material such as feed, grain or the like may be fed to and through compacting means, and sheeting means and then transversely cut and longitudinally split or cut by a shredding means. My present invention is confined to the compacting or compressing means coöperating with the sheeting or flattening means since as is well known such coöperating means may be used in the machine of Serial No. 25,174 or in similar machines or these coöperating means may under some circumstances constitute the entire machine as in the molding of plastic materials, bread or minor plastics and the like, wherein the flattened sheet of material is not to be further manipulated in the machine.

My invention stated in general terms comprises a means for compressing loose or relatively loose material and a means coacting with the compressing means whereby the material may be further compressed and sheeted, without, however, increasing the transverse plane or width of the sheeted material.

My invention further consists in so arranging the compressing means and the sheeting means that upon the passage of relatively thick foreign substances or extraneous matter with the material through the two means, both means may temporarily and simultaneously adjust themselves to per-

mit of the passage of the foreign substances, without altering their coöperative relationship.

The nature and scope of my invention will be more fully understood from the following description taken in connection with the accompanying drawings forming part hereof, in which,

Figure 1, is an elevational view, partly sectioned, of the discharge end of the device embodying main features of my invention.

Fig. 2, is a side elevational view thereof.

Fig. 3, is a longitudinal sectional view taken on line *a*, *a*, of Fig. 1.

Fig. 4, is a transverse sectional view taken on line *b*, *b*, of Fig. 2, and

Fig. 5, is a cross-sectional view taken on line *c*, *c*, of Fig. 2.

Referring to the drawings 1, 1, represent the side frames of the machine, and 2, 2, the uprights or standards mounted on frames 1 and constituting the support for the shaft 3 of the upper compressing roll 4. The shaft 3 has its bearings in boxes 5 sliding up and down in the uprights 2 and maintained under tension of springs 6 controlled by the tension screws 7. The shaft 8 of lower roller 9 has fixed bearings in the side frames 1. A belt 10 partly incloses the roller 9, the roller 9 being in fact the driving mechanism for the conveyer or belt 10.

Loosely supported on the shaft 3 outside the respective ends of the roller 4 and inside the uprights 2 are the two forwardly curved bracket arms 11 each having a curved slot 12 intermediate of its ends and each arm 11 having at its upper end an offset 13 arranged to oscillate slightly between the uprights 2 and to bear on the rear of said uprights to prevent other than the required slight oscillation rearward. To the lower end of the bracket arms 11 is secured a plate 14 the under face of which is fluted or convoluted as at 15. Each bracket arm 11 is connected with a transverse bar 16 by means of pins or rollers 17 extending from lugs 18 of bar 16 into and through the slots 12 of the bracket arms 11. The transverse bar 16 is arranged to slide upon the front face of uprights 2 and is maintained in proper position on said uprights 2 by means of spring 19 interposed between plate 14 and bar 16. A tension screw 20 serves to adjust the tension of the spring 19. The plate 14 forms the upper or movable jaw for a

sheeting mechanism. The lower jaw 21 is fixed to the frame 1 of the machine in co-operation relationship to the upper jaw 14 and the lower jaw 21 has its upper face convoluted or fluted as at 22 to correspond complementally with the fluted face 15 or upper jaw 14. While said jaw 21 is relatively fixed with respect to the frame 1 it is pivotally supported below its delivery end upon a transverse rod 23. A slotted ear or extension 24 on each end of the jaw 21 is bolted by bolts 24^a to the frame 1. By raising or lowering the ears 24 the jaw swings on the rod 23 and the face 22 of the jaw 21 may be brought away from or toward the face 15 of jaw 14, the jaw 21 rocking slightly upon the transverse rod 23 as a pivot. By this means the distance between the entrance end of jaws 14 and 21 may be adjusted to sheet or flatten or even comminute or pulverize loose material as it comes from rollers 4 and 9 to the required thinness.

The lower roller 9 around which belt conveyer 10 is passed, has its ends flanged as at 25 26 the flanges being inwardly beveled so as to confine the material passing between the rollers 9 and 4 against spreading transversely during the compression of the materials and the convoluted coacting faces of 30 the sheeting jaws permit of the necessary expansion of the material when flattened without however increasing the distance measured on a horizontally extended plane passing through the center of the flattened sheet.

The undulated or fluted jaws of the discharge make it possible for the material to be cut with the cutting instrument approaching or cutting from any angle. It will be seen that if the cutter be brought against the material at right angles to the plane of the sheet of material the material is held firmly in place and cannot escape the cutting instrument at any point, while if the instrument be used for cutting parallel to the plane of the material the undulation or corrugations hold the material in such way that the instrument is at no time passing through the full thickness of the sheet material.

50 The under edges of each jaw 14 and 21 diverge more or less at the entrance end to

the sheeting mechanism so that as the material passes through the jaws it is gradually flattened prior to the final flattening and corrugating of the material at the exit end of the jaws.

When a foreign substance such as a stone, nails or similar obstruction passes with the material under the roller 4, said roller is forced upward, while the upper jaw 14 is maintained in position by the movement forward of the arms 11 about the roller 18, the arm 11 being constructed so as to hinge on the shaft of the roller 4. When the roller 4 is forced upward the arm 11 swings about 18 as a pivot and maintains the pressure on the jaw 14. When the foreign substance has passed under and from contact with roller 4 and between the jaws, the roller is held in elevated position and the sheet of material is momentarily withheld from passing from between the jaws.

Having thus described the nature and objects of my invention, what I claim as new, and desire to secure by Letters Patent, is,—

1. In a device of the character described, a means for compressing relatively loose material and two sheeting jaws coöperating with said compressing means said jaws having their coacting faces at the exit end convoluted complementally whereby the material may be further compressed and sheeted during its passage through said jaws without projecting the material transversely beyond the sides of the compressing means and sheeting jaws.

2. In a device of the character described, an upper compacting roller, a shaft carrying the same, vertically adjustable bearings for the shaft, slotted bracket arms supported at one end by the shaft, a plate, constituting an upper sheeting jaw, carried by the other end of said bracket arms, and means carried by the bracket arms and by the jaw whereby angular displacement of the jaw with respect to the vertical movement of jaw and roller is prevented during an upward movement of said jaw.

In testimony whereof I have signed my name to this specification.

ROBERT A. STUBBS.
